CLAIM

The ornamental design for a needle holder for endoscopic surgery, as shown and described.

DESCRIPTION

FIG. 1 is a front perspective view of a needle holder for endoscopic surgery showing our new design in an opened state;

FIG. 2 is a front perspective view of the needle holder for endoscopic surgery of FIG. 1 shown in a closed state thereof; FIG. 3 is a front view of the needle holder for endoscopic surgery of FIG. 1, the rear view being a mirror image thereof;

FIG. 4 is a top plan view thereof;

FIG. 5 is a bottom plan view thereof;

FIG. 6 is a left side view thereof;

FIG. 7 is a right side view thereof; and,

FIG. 8 is a front view of the needle holder for endoscopic surgery of FIG. 2.

The broken lines show portions of the needle holder for endoscopic surgery that form no part of the claimed design.
